(57) **CLAIM**

The ornamental design for a drapery rod adapter, as shown.

DESCRIPTION

FIG. 1 is a cross-sectional view of the drapery rod adapter cut along line 1—1 of FIG. 4, it being partially shown for ease of illustration;

FIG. 2 is a reduced scale perspective view thereof;

FIG. 3 is an enlarged end view of the drapery rod adapter; FIG. 4 is a reduced scale front view of the drapery rod adapter;

FIG. 5 is a reduced scale top view of the drapery rod adapter; FIG. 6 is a reduced scale back view of the drapery rod adapter; and,

FIG. 7 is a reduced scale bottom view of the drapery rod adapter.

The broken line showing of an internal structure is for illustrative purposes only and forms no part of the claimed design.
